UNITED STATES PATENT OFFICE.

NORMAN W. NUTT, OF TRENTON, NEW JERSEY.

ELECTRIC SWITCH.

1,366,700.

Specification of Letters Patent. Patented Jan. 25, 1921.

Application filed June 14, 1919. Serial No. 304,148.

To all whom it may concern:

Be it known that I, NORMAN W. NUTT, a citizen of the United States, residing in Trenton, in the county of Mercer and State of New Jersey, have invented an Improvement in Electric Switches, of which the following is a specification.

The invention relates to quick action snap switches adapted to open and close an electric circuit with a rapid snap action to avoid 10 sparking at the contacts, and is particularly adapted for use in lamp sockets intended to carry a relatively heavy wattage current without danger of arcing between the switch terminals. The principal object of the invention is to provide a relatively simple and 15 efficient snap switch of the character indicated, involving comparatively few elements, which are so constructed and arranged as to 20 avoid undue wear or derangement, and in which a partial rotation of the switch spindle will first initiate a disengagement of a 25 rotary switch plate from a locking plate and exert tension on the switch plate, by means of a spring connection between the same and the spindle which spring has been previously 30 put under tension by the initial turning of the spindle; so that the switch plate will be given a partial rotation, preferably 90°, 35 when it is again locked to the locking plate, the opening and closing rotary movement of the switch plate being effected so rapidly that arcing between the terminals of the switch plate and the fixed contacts or terminals is practically 40 eliminated.

The invention is illustrated in the accompanying drawings, in which,

Figure 1 is a longitudinal section of a lamp socket, the outer shell or casing being 45 omitted.

Fig. 2 is a vertical elevation of the switch plate and the cam or dog adapted to lift the same.

Fig. 3 is a similar view of the switch plate per se.

Fig. 4 is a longitudinal section through the same.

Fig. 5 is a longitudinal section through the cam coöperating with the switch plate.

Fig. 6 is an elevation of the same.

Fig. 7 is a longitudinal section through the locking plate.

Fig. 8 is an elevation of the same.

Fig. 9 is a vertical elevation of the switch plate showing the actuating springs connecting the same with the shaft.

Fig. 10 is a detail view of the switch spindle.

Referring to the drawings, the numerals 1 and 2 indicate the upper and lower halves of a lamp socket supporting base formed of molded porcelain or any other suitable insulating material, the contacting faces of said members being provided with grooves or channels which constitute bearings for the shank of a key spindle, when the two halves of the base are secured together by screws in the usual manner. The upper section 1 of the base carries the usual spring contact 20 connected with wire terminal 21, and the lower section is provided with the spring contact 22 having the usual center contact 23 within the screw-threaded socket 24. The engaging faces of the members 1 and 2 on the handle side of the socket are extended to 75 constitute an elongated bearing for the cylindrical portion of the spindle 3, the inner end of which is forked or bifurcated as at 3' and is generally rectangular in cross section, and the outer end of which is provided with the usual thumb piece 19. Mounted on the cylindrical portion of the spindle 3 is a washer 18, which abuts lugs or projections 17 formed on the spindle and which serves to accurately space the spindle in the base, as indicated in Fig. 1, said washer engaging the inner end of the bearing in which the spindle rotates.

Loosely mounted on the forward or bifurcated end of the spindle 3, so as to be capable 90 of longitudinal movement thereon, or rotative movement independently thereof, is a switch plate 4, which is preferably formed as a stamping from sheet metal, having a central annular portion with two oppositely 95 disposed lateral arms having contacts 5 disposed at right angles thereto for coöperation with the spring contacts 22 and 20, and two shorter arms at right angles to the contact arms and terminating in upturned ears 6, 6. The center of the switch plate is recessed as 100 at 8 to permit said plate to move freely either axially or circumferentially with respect to the spindle. The long arms of the switch plate are provided with detents 7, 7, 105 which are preferably formed as bosses pressed outward from the rear of the plate, as more particularly illustrated in Fig. 4. Between each of the detents 7 and the center of the switch plate is formed a similar 110 boss 7' which constitutes a cam member by means of which the switch plate is moved

axially of the spindle, as will be herein-after explained.

The switch plate is operatively connected with the spindle 3 by means of two spiral springs 15 and 16, one end of which is secured in the bifurcated portion 3' of the spindle 3, in any suitable manner, as shown in Figs. 1 and 9, and the other ends of the respective springs being attached to the lugs 6, 6 on opposite sides of the switch plate, as clearly shown in Fig. 9, so that when the spindle is turned in one direction, one spring is placed under tension and when turned in the opposite direction the other is put under tension, and both tend to rotate the switch plate. Obviously instead of the dual spring arrangement as illustrated, a single spiral spring may be employed, but the double arrangement is found preferable in that it produces a smoother and more positive snap action. In order to conserve space, the two springs are nested or disposed so that the convolutions of one lie within those of the other, as indicated in Figs. 1 and 9.

25 Located within a squared recess formed in the base concentric with the spindle 3 is a stop plate 9 having a dished central portion with an enlarged opening 10 and its sides forming a square which conforms to the recess in the walls of the base within which said locking plate is rigidly held. Each peripheral edge of the locking plate is provided with a recess 11 the edges of which constitute stops with which the bosses 7, 7 on 30 the switch plate engage to retain the switch plate locked in either opened or closed relation.

Fixed to the squared end 3' of the spindle 3 and occupying the dished portion of the 40 stop plate 9 is a cam 12 having oppositely extending radial cam members and a central flange 14 provided with a squared opening 13 by means of which the cam is locked to the spindle for rotating movement but is 45 slidable thereon when the parts are to be assembled or adjusted. The radial fingers of the cam member 12 coöperate with the rounded cam-like bosses 7^a on the switch plate and serve to force the switch plate 50 axially along the spindle until the detent bosses 7 on the switch plate are disengaged from the stop members 11 on the stop plate 9.

From the foregoing description, it will be apparent that the mode of assembling, adjusting and operating the switch is as simple and effective as the construction and coordination of the various parts thereof, and may be described as follows. To assemble the various elements, the springs 15 and 16 60 are secured by their ends constituting the apices of the spirals, in the bifurcated member 3' of the spindle 3. The switch plate 4 is then slipped over the spindle and the free ends of the springs 15 and 16 secured to the 65 arms 6, 6 of the switch plate. The squared

end of the spindle 3 is then passed through the squared eye 13 in the cam 12, and the locking plate 9 is placed over the cam 12 so that the bosses 7, 7 of the switch plate engage two opposite stops 11 on the locking plate. 70 The spindle with its associated elements is then laid in the groove formed in one of the base members, so that the locking plate engages the squared recess therein and the several members, to wit, the switch plate 4, 75 the cam or dog 12, and the locking plate 9 are forced into intimate engagement by the tension exerted by springs 15 and 16, and the spindle is held against axial movement by the washer 18, which engages the extension on the wall of the base on one hand and the lugs or projections 17 formed on the spindle, on the other. The second member of the base is then applied and secured to its coöperating member by suitable screws or 80 other fastenings and the device as thus assembled is ready for application of the usual shell or casing.

As illustrated in Fig. 1, the switch is closed as the contact members 5, 5 of the 90 switch plate are in engagement with the spring contacts 20 and 22, located in the respective base members. It will be noted that the detents 7, 7 on the switch plate 4 are in engagement with two opposite stops 11, 95 11 on the locking plate 9. In order to open the switch, the spindle 3 is given a partial turn by means of the hand piece 19, the first effect of which is to put one of the springs 15, 16 under tension, which action tends to 100 rotate switch plate 4. The rotary movement of the spindle 3 rotates the cam 12 and causes the outer ends of the arms thereof to engage the bosses 7^a of the switch plate and thereby move the switch plate axially of the spindle 105 3 in opposition to the thrust of the springs 15 and 16 which disengages the detents 7, 7 from the stops 11 on the lock plate 9. As soon as this disengagement has been effected, the switch plate 4 responds to the rotative 110 stress imposed thereon by spring 15 or 16 according to the direction the spindle is turned, and executes a rapid partial rotation, thereby separating contacts 5, 5 from the spring contacts 20 and 22, movement of 115 the switch plate being continued through one quarter of a revolution until the detents 7, 7 on said switch plate engage the stops 11, 11 on the locking plate 9 at right angles to the stops from which the detents were first disengaged.

It will be apparent that one spring will operate the switch when the spindle is turned in one direction and the other will operate when the spindle is turned in the reverse direction.

From the foregoing, it will be apparent that a partial rotation of the spindle 3 in either direction will effect a quick separation of the movable and fixed contacts of the 130

switch members, so that to effect either the opening or closing of the switch, it is only necessary that the switch plate rotate through an angle of 90° , and to bring about this result, it is necessary only to turn the spindle until the dog 12 carried thereby engages the cam lugs or bosses 7^a on the switch plate and passes behind the same so as to lift the switch plate out of locking engagement with the locking plate, when the necessary throw of the switch plate through a quarter revolution is automatically effected by the action of the springs 15 and 16.

What I claim is:—

- 15 1. A snap switch comprising an axially movable rotary switch plate having detents thereon, fixed contacts coöperating therewith, a stationary plate having fixed stops coöperating with said detents, a rotary spindle, spring mechanism connecting the spindle and the switch plate, and means on said spindle to move the switch plate out of engagement with the stationary plate when said spindle is partially rotated in either direction.
- 20 2. A snap switch comprising an axially movable rotary switch plate having detents thereon, fixed contacts coöperating therewith, a stationary plate having fixed stops spaced at angles of 90° about the periphery thereof and coöperating with said detents, a rotary spindle, spring mechanism connecting the spindle and the switch plate, and means on said spindle to move the switch plate out of engagement with the stationary plate when said spindle is partially rotated in either direction.
- 25 3. A snap switch comprising an axially movable rotary switch plate having detents and bosses thereon, fixed contacts coöperating with said switch plate, a stationary plate having fixed stops coöperating with the detents on the switch plate, a rotary spindle, spring mechanism connecting the spindle and switch plate, and a cam fixed on the spindle to engage the bosses on the switch plate to release the latter from the stationary plate when the spindle is partially rotated in either direction.
- 30 4. A snap switch comprising an axially movable rotary switch plate having detents and bosses thereon, fixed contacts coöperating with said switch plates, a stationary plate having fixed stops spaced at angles of 90° about the periphery thereof and coöper-

ating with said detents, a rotary spindle, spring mechanism connecting the spindle and switch plate, and a cam fixed on the spindle to engage the bosses on the switch plate to release the latter from the stationary plate when the spindle is partially rotated in either direction.

5. A snap switch comprising a base, a rotatable spindle mounted therein, spaced contacts carried by the base, an axially movable switch plate loosely mounted on the spindle coöperating with said contacts and having detents thereon, spring mechanism connected to the spindle and to opposite sides of the switch plate, a cam fixed on the spindle, a stop plate fixed to said base having spaced peripheral fixed stops coöperating with the detents on the switch plate, and coöperating cam means on the switch plate adapted to be engaged by the cam on the spindle to move said switch plate axially of the shaft and unlock the switch plate from the stop plate when the spindle is partially rotated in either direction.

6. A snap switch comprising an axially movable rotary switch plate having detents thereon, fixed contacts coöperating therewith, a stationary plate having fixed stops coöperating with said detents, a rotary spindle, oppositely tensioned spiral springs connecting the spindle to opposite sides of the switch plate, and means on said spindle to move the switch plate out of engagement with the stationary plate when said spindle is partially rotated in either direction.

7. A snap switch comprising a base, a rotatable spindle mounted thereon, spaced contacts carried by the base, an axially movable switch plate loosely mounted on the spindle coöperating with said contacts and having detents thereon, and oppositely tensioned spiral springs connecting the spindle to opposite sides of the switch plate, a stop plate fixed to said base having spaced peripheral fixed stops coöperating with the detents on the switch plate, and coöperating cam means on the spindle and switch plate to move the latter axially of the switch and unlock the switch plate from the stop plate when said spindle is partially rotated in either direction.
